UNITED STATES PATENT OFFICE.

ABRAHAM H. GODKEVITCH, OF NEW YORK, N. Y.

WOODEN SHIPPING CASE.

1,423,317.

Specification of Letters Patent. Patented July 18, 1922.

Application filed November 15, 1921. Serial No. 515,221.

To all whom it may concern:

Be it known that I, ABRAHAM H. GODKEVITCH, a citizen of the Republic of Russia and resident of New York, in the county 5 of New York and State of New York, have invented certain new and useful Improvements in Wooden Shipping Cases, of which the following is a specification.

This invention relates to the type of construction covered by my prior patent 1,391,470, issued September 20th, 1921. Broadly considered, I seek to secure the same general objects by my present invention as those secured by my previous construction, namely 15 to prevent the case from being opened without leaving tell-tale evidence that it has been tampered with.

A further object of my present invention is to provide simple means for locking the 20 cover of the case at each corner to both of the two adjacent side walls, and at the same time lock the side walls together. Thus, when the cover is once closed, it cannot be removed, and neither can either the sides 25 or the ends be removed. My improved automatic locking device, in its preferred form, includes two members, one of which forms a rigid connection between the side and end walls, and the other, which is carried by the cover, automatically interlocks 30 therewith upon the closing of the cover.

In the accompanying drawings:—

Fig. 1 is a perspective view of a case in which my improved fastening means may 35 be employed,

Fig. 2 is a vertical section in the vicinity of one of the corners thereof,

Fig. 3 is a transverse section on the line 3—3 of Fig. 2,

Fig. 4 is a perspective view of one member 40 of the cover locking device, a part being removed,

Fig. 5 is a similar view of the inner side of the part removed from the member shown 45 in Fig. 4, but on a smaller scale.

Fig. 6 is a perspective view of a locking bracket which may be employed in each of the lower corners,

Fig. 7 is a perspective view of a securing 50 bracket which may be used in the corner intermediate of the top and bottom.

I have illustrated my invention as applied to a wooden shipping case having a cover 10, side walls 11, end walls 12, and 55 a bottom wall 13. The case may have bars 14 extending transversely of the boards of

the cover and bottom at each end thereof, and the side walls may have similar bars 15 extending vertically adjacent to each end and terminating at the ends of the bars 14. 60

The cover at each corner is provided with a locking member which includes a body portion preferably formed of heavy sheet metal and bent to form flanges 16 and 17 at right angles to each other, and a top 65 formed of overlapping flanges 18 and 19, one being directly integral with the flange 16 and the other directly integral with the flange 17. The two flanges or plate portions 16 and 17 carry a pair of pivoted dogs 70 or catches 20 and 21 mounted to swing toward and from the line or angle of intersection 22 of the two flanges or plate portions 16 and 17. These dogs are mounted on pivots 23—24, and are pressed away 75 from the angle in planes at right angles to each other by a spring 25. This spring is illustrated as having a loop portion secured to a pair of studs 26, and arm portions 27 engaging with the dogs adjacent to their 80 free ends. The locking member may also be provided with a plate portion 28 including two flanges at right angles to each other, and of approximately the same shape as the flanges 16 and 17. This angle plate 85 28 may be secured in place by the ends of the pivot pins 23—24, which may be shouldered and riveted over. It may also be held in spaced relationship to the flanges 16 and 17 by lugs 29 on the edges of said flanges 90 and which also serve as stops to limit the outward movement of the dogs. It will be noted that the ends of the flanges or plate portions 16 and 17, as well as the ends of the dogs 20 and 21, are tapered so as 95 to more effectively guide the device into position upon closing the cover.

Rigidly secured to the inner surface of the casing at each corner is a retainer which is preferably constructed substantially as 100 shown in Fig. 6. This includes terminal portions 30 which lie in planes at right angles to each other, and which may be directly bolted to the side and end walls of the case, and intermediate portions 31—32 105 which are adapted to lie adjacent to but spaced from said side and end walls of the case. The spacing of the portions 31—32 from the case walls, as well as the length of these portions, is such that the locking 110 member carried by the cover may slide down the inner surface of the case at the corner

between the portions 31-32 and the case wall. The retainer member is so positioned that when the cover reaches final position, the dogs 20-21 may swing away from the corner in planes at right angles to each other, and engage beneath the connecting portions 33-34 between the portions 31-32 and the terminal portion 30. This retainer member being rigidly bolted to both the side and 10 the end walls, effectively locks them together and prevents the removal of either the side wall or the end wall. It also serves to engage with the member of the locking device which is carried by the cover, so as to hold 15 the cover to both the side wall and the end wall. It will be noted that the dogs 20-21 engage beneath the portions 33-34 of the retainer, and that these portions are closely adjacent to the terminals 30 which are 20 directly bolted to the walls of the case. Thus the strain on the retainer member resulting from the attempt to raise the cover, comes adjacent to the point where such strain can be most effectively resisted, 25 namely at the securing bolts.

It will of course be evident that the same locking means may be employed at each of the four lower corners for holding the bottom in place as is employed at each of the 30 four upper corners for holding the cover in place, but ordinarily this is not necessary, and I employ a bracket which may be constructed substantially as shown in Fig. 7, and which is similar in most respects to 35 the body portion of the locking member carried by the cover. That is, it is formed of sheet metal bent to form a pair of flanges or plate portions 36-37, which may be bolted to the side and end walls, and a 40 bottom portion formed of superposed flanges or plate portions 38-39, one directly integral with the part 36 and the other directly integral with the part 37, and secured together and to the bottom by a suitable bolt. 45 For preventing the removal of any one of the intermediate boards of the side or end walls, I may provide intermediate brackets including angle strips 40, the two flanges of which may be directly bolted to the side and 50 end walls of the case. There may be as many of these angle brackets as there are intermediate boards in said side and end walls.

The necessity for employing these intermediate bracket members may be avoided and the intermediate boards of the bottom and top effectively secured in place if the case be provided with bars 14 and 15 enclosing the case adjacent to the opposite 55 ends. Although these bars may be omitted in some cases, it will be obvious that when they are employed the locking members are bolted through the walls to these bars, and that therefore the locking members serve to 60 connect the parts together as two bands en- 65

circling the case, and effectively prevent the removal of any of the boards of the top, bottom or side walls.

Having thus described my invention, what I claim as new and desire to secure by Letters Patent is:-

1. A shipping case having a fastening device including a member secured to and engaging a side and an end wall of the case at a corner, and a member secured to the third 75 wall at said corner, and engaging with said first mentioned member to lock said third wall to both of the other two walls upon the closing of the case.

2. A shipping case having a cover provided with a pair of catch members projecting downwardly therefrom at the corner, and means secured to the inner surface of the end wall and to the inner surface of the 85 side wall for interlocking engagement with said catch members upon the closing of the case.

3. A shipping case having a cover provided with a pair of depending flange members in planes at right angles to each other and positioned to lie adjacent to the inner surfaces of a side and an end wall at a corner of the case, and means carried by said flange members for interlocking engagement with the side and end walls upon the closing of 95 the case.

4. A shipping case having a cover provided with a pair of depending flange members in planes at right angles to each other and positioned to lie adjacent to the inner 100 surfaces of a side and an end wall at a corner of the case, and a pair of pivoted catches secured to said flanges for interlocking engagement with the side and end walls upon the closing of the case. 105

5. A shipping case having a cover provided with a pair of depending flange members in planes at right angles to each other and positioned to lie adjacent to the inner surfaces of a side and an end wall at a corner of the case, a pair of catches pivotally mounted on said flange members and movable in planes at right angles to each other, and a retainer member secured to the side and end walls of the case for interlocking 115 engagement with both of said catches.

6. A shipping case, including a member having a pair of catches secured thereto and movable in planes at right angles to each other and adapted to lie adjacent to the 120 inner surfaces of two intersecting walls of the case at a corner, and a member for interlocking engagement with said catches to prevent the opening of the cover after it has once been closed. 125

7. A shipping case having a pair of interengaging members positioned at a corner thereof, one of said members being secured to the cover of the case, and the other being secured to the inner surface of the side and 130

- end walls, and one of said members having a pair of pivoted catches movable in planes at right angles to each other adapted to interlock with the other member.
- 5 8. A locking means for shipping cases, including a pair of flanges adapted to be secured to the inner surface of the cover in planes at right angles to each other, a pair of catches pivoted to said flanges, and a
- 10 strap member having its end portions adapted to be secured to the inner surfaces of the end and side walls of the case and having an intermediate portion spaced from said side and end walls at the corner to receive said
- 15 flanges and catches, and automatically engage with the latter.
9. A locking means for shipping cases, including a pair of flanges adapted to be secured to the inner surface of the cover in
- planes at right angles to each other, a pair 20 of catches pivoted to said flanges, and a member adapted to be secured to the side and end walls of the case for interlocking engagement with said catches.
10. A locking device for shipping cases, 25 including a member adapted to be secured to the inner surface of the cover and presenting a pair of pivoted catches movable in planes at right angles to each other, and a member adapted to be secured to the inner 30 surface of the side and end walls of the case for connecting the latter, and having spaced portions for interlocking engagement with said catches.

Signed at New York in the county of New 35 York and State of New York this 14th day of November A. D. 1921.

ABRAHAM H. GODKEVITCH.
